CONTACT MOUNTING MEANS

Original Filed April 9, 1920

FIG. 1.

FIG. 2.

INVENTOR
S. M. Day,
BY
Neil H. Tolston,
his ATTORNEY

UNITED STATES PATENT OFFICE

SALISBURY M. DAY, OF ROCHESTER, NEW YORK, ASSIGNOR TO GENERAL RAILWAY SIGNAL COMPANY, OF ROCHESTER, NEW YORK, A CORPORATION OF NEW YORK

CONTACT-MOUNTING MEANS

Original application filed April 9, 1920, Serial No. 372,585. Divided and this application filed September 22, 1926. Serial No. 137,138.

This invention relates to contacts for use in relays of various types and has more particular reference to means for mounting a contact on a carrying arm.

5 The present application is a division of applicant's co-pending application Ser. No. 372,585 filed April 9, 1920, for "Improvement in relays."

Among the objects of this invention are to 10 provide economical, secure, and simple means for connecting a contact to a carrying arm and at the same time to provide a good electrical conducting connection between the contact and the arm.

15 Further objects, purposes and characteristic features of the invention will appear as the description progresses, reference being had to the accompanying drawing, showing solely by way of example, one form which the invention may assume, and wherein:

20 Fig. 1 is a sectional detailed view, of a part of the device.

Fig. 2 is a side elevation of a device constructed in accordance with the present invention.

25 Referring to the drawings, a support bracket 60, carried by the usual top plate of a relay, carries a screw 62 held in its lower end by means of a nut 63, which screw has 30 a disc-like contact 64 mounted on its head and formed of a non-corrosive, highly conductive metal, such as coin silver or the like.

35 A contact finger 34, connected to a carrier bar or electro-magnet armature in any usual manner, has riveted thereto a spring arm 51, to the end of which is fastened a contact block 67. A reduced extended portion of the finger 34 is bent downwardly to bear against the spring arm 51 and prevent its flexing in one 40 direction.

The contact button 67 is preferably formed 45 of carbon of a hard crystalline structure, and is impregnated with a small percentage of copper to increase its conductivity. Care is taken to not add too great a percentage of copper in order that all possibility of fusing of the contacts and resulting sticking of the same, be avoided. The button 67 has beveled edges and fits into a sheet metal cup 68 having 50 its edges spun over around the button to

firmly hold it within the cup. Two spaced arms 69 are stamped out of the bottom of the cup and are passed through spaced slots 51¹ in the spring arm 51 and are then bent toward each other against the rear side of the spring arm, as shown. Solder 69¹ is run into the joint between the two arms 69 and the back of the spring arm 51, to firmly interconnect all three and insure a good conducting connection between the cup and the arm 51.

55 With the construction described above a ready and secure means is furnished for connecting the button 67 to its carrying arm 51, and a good electrical connection is formed between the button and its carrying arm.

60 The above specific description of the present invention is given solely by way of illustration and is not intended in any manner whatsoever in a limiting sense. Obviously this invention can assume many different forms 65 and is susceptible of various modifications, and all such forms and modifications are contemplated as being included by this invention as come within the scope of the appended claims.

70 Having described one form of my invention, I now claim:

75 1. A carbon contact for relays comprising a spring having spaced slots therein, a carbon button with a beveled edge, and a cup receiving said button and having its edge spun over the edge of the button, said cup having prongs stamped out of its bottom which extend through said slots and are bent back to hold the cup in place.

80 2. In a relay contact, a carrier arm, spaced slots in the carrier arm, a cup, arms stamped out of the bottom of the cup, passed through said slots, and bent towards each other against the rear side of the carrier arm, and a contact button fixed in the cup.

85 3. In a relay contact, a carrier arm, spaced slots in the carrier arm, a cup, arms stamped out of the bottom of the cup, passed through said slots, and bent towards each other against the rear side of the carrier arm, and a contact button fixed in the cup, and solder connecting the ends of the arms to each other and to the rear side of the carrier arm.

90 4. In a relay contact, a carrier arm, spaced

- slots in the arm, a cup, a contact having a beveled edge and rigidly and non-removably held in the cup by spinning the edge of the cup over said edge, narrow integral arms stamped out of the cup whereby to leave a large portion of the cup base to support the base of the contact passing through the slots in the carrier arm and bent over to hold the cup tightly to the arm, and solder connecting the ends of the arms to each other and to the rear of the carrier arm, whereby to form a permanent and low resistance electrical connection between the carrier arm and said contact.
5. In a relay, a contact button, a cup non-removably carrying the button, an arm, slots and cooperating integral lugs carried by the cup and arm for fastening the cup to the arm, and non-removable connecting means between said cup and arm.
- 10 20

In testimony whereof I affix my signature.

SALISBURY M. DAY.
